UNITED STATES PATENT OFFICE.

SAMUEL M. CARMEAN AND JAMES H. CARMEAN, OF KANSAS CITY, MISSOURI

ELECTRIC HEATER.

Application filed April 30, 1926. Serial No. 105,705.

Our invention relates to electric heaters and more particularly to a heater that includes a heating element and a fan for blowing a current of air into engagement with the heating element.

It is a purpose of our invention to provide new and improved means for mounting a fan of standard construction in a heater of the above mentioned character, that is simple in construction and which does not interfere with the flow of air through the heater. As is well known, it is necessary in order for a fan to operate efficiently that there be no obstacles either in front or in back of the blades to interfere with the flow of air or the drawing of air toward the blades during rotation thereof, and our new and improved mounting for the motor of the fan is such that the minimum of interference with the flow of air results.

It is another purpose of our invention to provide a heater of the above mentioned character with a casing having a strengthening and air deflecting ring that also serves to hold the heating element in place.

Other objects and advantages of the invention will appear as the description of the accompanying drawings proceeds. However, we desire to have it distinctly understood that we do not intend to limit ourselves to the exact details shown or described, but that we intend to include as part of our invention all such obvious changes and modifications of parts as would occur to a person skilled in this art and as would fall within the scope of the claims.

In the drawings:—

Fig. 1 is a perspective view of our improved heater, partly broken away.

Fig. 2 is a longitudinal, sectional view thereof.

Fig. 3 is a section taken on the line 3—3, of Fig. 2, and

Fig. 4 is a perspective view of our improved motor fan mounting member.

Referring in detail to the drawings:

Our improved electric heater is shown as comprising a casing 10 which is preferably substantially cylindrical and which is provided with a base portion 11 and a handle 12. Screen members 13 and 14 are mounted on opposite ends of the casing, the screen member 14 being carried by a ring-like mem-

ber 15 which is secured to the casing in any desired manner.

Mounted within the casing is a supporting spider 16 for the heating element 17 having the terminals 18 from which the conductors 19 lead to the switch 20. Mounted so as to blow a current of air over the heating coils 17 within the casing 10 is a fan having a motor 21 and the fan blades 22. The fan is of a standard construction and is provided with a saddle member having the laterally extending wings 23 and a depending ear 24 by means of which the same may be mounted on a suitable support.

In order to properly support the fan within the casing 10, means is provided in the casing for supporting the motor by means of the ear 24. Said means comprises a bracket 25 which is provided with the slightly curved base flanges 26 and 27, said flanges conforming substantially to the curvature of the inner face of the casing 10 and the base flange 26 being longer than the base flange 27 to offset the upstanding portion 28 of the bracket from the central, vertical plane of the heater, as clearly shown in Fig. 3. This is done so that the upstanding portion 28 has the proper relation to the ear 24 to locate the motor and fan centrally in the casing so that the axis of rotation of the fan is on the axis of the casing. The upstanding flange portion 28 is provided with an opening 29 that aligns with an opening in the ear 24 and through which a fastening member such as the bolt 30 may be passed for securing the ear 24 to the upstanding flange portion 28. It will be noted that the member 28 is relatively thin and wide, and that the same extends with the width thereof lengthwise in the casing 10 so that the flow of air through the casing from end to end thereof is not materially interfered with by the supporting member 25. The upper end of the upstanding flange portion 28 is provided with a pair of projections 31 between which lies a recess 32 that has a bevelled wall portion 33. One of the wings 23 of the supporting bracket on the motor 21 extends through the recess 32 and due to the offset arrangement of the upstanding portion 28, the wing portion 23 extends at an oblique angle where the same passes through the recess 32. For this reason

the wall 33 is bevelled so as to conform to the shape of the wing 23 where the same is in engagement therewith. Furthermore, by providing the projections 31 a firm support 5 for the motor 21 at spaced points is obtained, thus causing the motor to seat firmly on the end of the supporting member 25 without making it necessary to do any machining of the member 25. It will also be noted that 10 the casing 10 is split as at 9 and that the bracket member 25 serves as means for securing the free edges of the casing together. The casing is also provided with a strengthening ring 34 that has an inturned flange 15 35 serving as means for deflecting the air set in motion by the fan so as to prevent undesirable lateral spreading of the same and to concentrate the same into a well defined stream. The wire screen 13 is preferably 20 also carried by said flange. The ring 34 has an outturned flange 36 engaging the edge of the casing 10 and is secured in place by the bolts 37. The ring 34 is readily slipped in place and serves as a retaining ring for 25 the spider 16 which is held in position between the screws 38 and said ring 34.

What we claim and desire to secure by Letters Patent is:

1. In a heater, a motor, a motor mounting 30 comprising a bracket having a base portion and an upstanding portion offset from the vertical plane of the axis of the motor, an ear on said motor in the vertical plane of its axis and means for securing said ear to the upstanding portion of said bracket.
2. In a motor mounting, a frame, a motor, and means for mounting said motor on said frame, comprising a bracket secured to said frame having an upstanding portion provided with a recess in the end thereof, a

bracket having wings secured to said motor and having a depending ear, and means for securing said ear to said upstanding portion, one of said wings lying in said recess.

3. In a motor mounting, a casing, a motor, 45 and means for mounting said motor in said casing, comprising a bracket secured to said casing having an upstanding portion provided with a recess in the end thereof, a bracket having wings secured to said motor and having a depending ear, and means for securing said ear to said upstanding portion, 50 one of said wings lying in said recess and the upstanding portion of said first bracket engaging the motor on opposite sides of said 55 recess.

4. In a heater, a casing, a motor, and means for mounting said motor in said casing, comprising a bracket secured to said casing having an upstanding portion provided with a recess in the end thereof, a bracket having wings secured to said motor and having a depending ear, and means for securing said ear to said upstanding portion, one of said wings lying in said recess, 65 said recess having a bevelled wall portion.

5. In a device of the character described, a casing, a motor, and means for mounting the motor in the casing, comprising a base portion fixed to the casing, an upstanding 70 bracket on the base portion offset from the central vertical plane of the casing, the motor being positioned with its axis in said plane and having a depending ear in said plane, and means for securing said ear to 75 the bracket.

In testimony whereof we affix our signatures.

SAMUEL M. CARMEAN.
JAMES H. CARMEAN.
